[57] **CLAIM**

The ornamental design for a decorative edging block, as shown and described.

DESCRIPTION

FIG. 1 is an isometric view of a decorative edging block incorporating my new design;

FIG. 2 is a top plan view thereof;

FIG. 3 is a left side elevation view thereof, the right side elevation view being a mirror image;

FIG. 4 is a rear end view thereof;

FIG. 5 is a front end view thereof; and,

FIG. 6 is a bottom plan view thereof.

The broken line showing of the environment is for illustrative purposes only and forms no part of the claimed design.
